UNITED STATES PATENT OFFICE.

JOHN M. ROHLING, OF ST. LOUIS, MISSOURI, ASSIGNEE TO AMERICAN CAR AND
BOUNDRY COMPANY, OF ST. LOUIS, MISSOURI, A CORPORATION OF NEW JERSEY.

COUPLING-CENTERING DEVICE.

1,256,166.

Specification of Letters Patent. Patented Feb. 12, 1918.

Application filed June 15, 1917. Serial No. 174,923.

To all whom it may concern:

Be it known that I, JOHN M. ROHLING, residing at city of St. Louis, State of Missouri, and being a citizen of the United States, have invented certain new and useful Improvements in Coupling-Centering Devices, of which the following is a full, clear, and exact description, such as will enable others skilled in the art to which it appertains to make and to use the same, reference being had to the accompanying drawings, which illustrate the preferred form of the invention; though it is to be understood that the invention is not limited to the exact details of construction shown and described, as it is obvious that various modifications thereof within the scope of the claims will occur to persons skilled in the art.

In said drawings:

20 Figure 1 is a front elevation of my coupler centering device shown as applied to a fragmentary portion of the end sill of a car, parts of the striking plate casting being broken away and shown in section to better illustrate the relation of the rockers, their seats and the carry iron.

Fig. 2 is an inverted plan view of the right hand portion of Fig. 1.

30 Fig. 3 is a vertical section through the striking casting, carry iron and the affiliated parts, being taken on the line 3—3 of Fig. 1.

Fig. 4 is a similar vertical section, except that it is taken on the line 4—4 of Fig. 1; 35 and

Fig. 5 is an enlarged fragmentary view showing various coöperating relations between the rocker seats in the striking casting, the rockers and the carry iron.

40 My present invention relates to means for supporting and centering car couplers, it being a purpose to form suitable seats in a member adapted to be supported on or near the end of a car, and to mount a carry iron 45 upon rockers supported to rock on such seats.

The arrangement is such that the rockers and carry iron are linked together without the use of extraneous devices, and so 50 that they mutually coöperate to preserve their mutual relation.

The rockers and the carry iron are adapted to sway in unison in response to the lateral movement of a coupler supported by 55 the carry iron. Parts of the carry iron and

the rockers, together with portions of the rocker seats, co-act to so correlate the movable parts that they are responsive to gravity, and through this medium automatically center the coupler, whenever its deflecting influences cease or are sufficiently abated.

Friction is minimized and the carry iron may be supported at different heights by reversing some of the parts.

Other features and advantages will appear hereinafter and, of course, are included within the scope of the invention.

Referring to the drawings, the coupler centering device is shown as secured to a channel-shaped end sill 1, a portion of the web and the lower flange 2 of which is cut away to receive a striking plate casting 3. Said striking plate is in general of inverted U-shape formation and comprises a rear vertical wall 4 riveted or otherwise secured to the web of end sill 1, a forward or front vertically disposed wall 5 spaced in advance of rear wall 4, outer side walls 6, inner side walls 7 and an upper horizontal web 8 connecting the upper portions of front and rear walls 5 and 4, respectively, and having a rear general extension 8^a projecting back of end sill 1 and between draft sills 9. Connection between the front and rear walls 5 and 4, respectively, is further strengthened by reinforcing ribs 28.

Depending from the rear extension 8^a of the striking plate horizontal web 8, are side walls 10 lying against and secured to the webs of draft sills 9 and being provided with bottom flanges underlying the flanges of said draft sills 9. In the spaced vertical legs of the striking plate casting 3, the portions of the outer wall 5 contained therein are arched or curved to improve the strength of the wall at these locations, and the portions of the rear and forward walls 4 and 5, respectively, that are within said legs, project in their lower portions toward each other to form spaced rocker seats 11.

Projecting below said rocker seat in the front wall 5 of each leg, is an extension 12 and projecting below the rocker seat in the rear wall 4 in each leg is a similar extension 13, extensions 12 and 13 being suitably connected as by bolts 14.

The outer side walls 6 of the vertical legs of the striking plate casting 3, are provided with flanges 15 secured to the bottom flange 2 of end sill 1, said flanges 15 being rein-

forced and braced by ribs 16 connecting them with the lower portions of side walls 6. Said side walls 6 also contain apertures 17 through which may be passed rockers 18, one of said rockers being positioned in each leg of the striking casting 3 to be supported by the internal rocker seats 11 therein. Each rocker 18 is double-ended and is provided with oppositely projecting intermediate trunnions 19 having straight or flat surfaces adapted to bear on rocker seats 11, which rocker seats have protuberant arcuate bearing surfaces 20. The end portions of rocker seats 11 are upturned to form stops 21 for the rockers 18.

As best illustrated in Figs. 1, 4 and 5, each end of rocker 18 has a flat bearing surface 22 lying between outwardly projecting flanges 23 which form grooves at those ends.

Trunnions 19 of rockers 18 are positioned nearer one rocker end than the other, so that said rockers may be reversible and be adapted to support a carry iron 24 at a greater or less height from the top of the rails 25 or of the track. Carry iron 24 has a central U-shaped portion 25 adapted to receive and embrace the shank of the coupler indicated at C in Fig. 1. Progressing outwardly toward its opposite ends, carry iron 24 is of a more or less inverted U-shape form and is provided on its under side with protuberant arcuate rocker bearing surfaces 26. Rocker bearing surfaces 26 of carry iron 24 contact with the uppermost flat surfaces 22 of the ends of rockers 18 and lie in the groove formed by said straight surfaces 22 and the terminal flanges 23 of the rockers 18. The ends of carry iron 24 project outwardly beyond the upper ends of rockers 18 and have depending hooks or stops 27 adapted to engage said rocker ends. It will, therefore, be seen that the opposite ends of carry iron 24 are held in rocking engagement with the upper ends of rockers 18 and against separation and lateral displacement in connection therewith.

In assembling the coupler centering device, bolts 14 may be removed and the carry iron 24 may be slipped upwardly between the extensions 12 and 13 of the forward and rear walls 5 and 4, respectively, that lie within the vertical leg portions of striking casting 3. By reason of the space between extensions 12 and 13 and the apertures 17 in side walls 6, the spaced vertical legs of striking casting 3 are bifurcated and to such an extent that carry iron 24 may be inserted therebetween to a sufficient height to permit the rockers 18 to be inserted through openings 17 in side walls 6. Said openings 17 are of greater width in their lower portions to permit the passage of rocker trunnions 19, said wider lower portions having considerable height, as

shown in Fig. 4, to give adequate clearance and obviate the necessity of a careful passage of rockers 18 through said apertures 17. After the rockers 18 have been positioned so that the under flat surfaces of their trunnions 19 rest upon the arcuate bearing surfaces 20 of the rocker seats 11, carry iron 24 may be lowered so that its arcuate bearing surfaces 26 may enter between the uppermost flanges 23 of rockers 18 and rest upon the adjacent straight bearing surfaces 22, suspending said carrying iron between rockers 18. Thereafter, bolts 14 may be replaced to unite the lower extensions 12 and 13 of the vertical striking plate legs.

When connected cars are on a straight piece of track so that the coupler shank C is in its normal undeflected position, the parts of the centering device will assume the positions illustrated in Fig. 1. When such connected cars are in motion and the coupler shank C is caused to swing laterally, carry iron 24 which embraces this shank is similarly swung in the same direction that the coupler shank moves. As a result, the rocker 18 in each vertical leg of striking casting 3 rocks on its bearing seats 11 in the striking casting and both of said rockers will be inclined in the same direction. As is well depicted in Fig. 5, each rocker will be restrained from excessive tilting by one or the other of the upturned ends 21 of rocker seats 11, which ends serve as stops.

The inclined positions that the rockers 18 assume are limited by stops 21 to a degree that causes the articulated rockers 18 and carry iron 24 to always remain under the influence of gravity as exerted through the weight of the carry iron 24 and the coupler shank C. Consequently, as soon as the coupler deflecting influences are sufficiently relieved, carry iron 24 and rockers 18 automatically sway back to the positions indicated in Fig. 1, thereby centering the coupler C.

From the foregoing it is apparent that I have devised a coupler centering device comprising a plurality of rugged members loosely articulated so as to sway in unison and in a friction-minimizing manner. It is also clear that these parts retain their operative positions and co-act without being connected by extraneous devices. Their relation to the striking plate casting 3 is such that they are unable to become dislodged and inoperative, thereby acquiring the virtue of constant reliability.

What I claim is:

1. In combination in a coupler-centering device, a striking plate provided with seats on opposite sides of a coupler opening, upwardly directed rockers bearing on said seats, and a carry-iron suspended from said

- rockers adapted to impart parallel motion to said rockers.
2. In combination in a coupler-centering device, a striking plate provided with seats on opposite sides of a coupler opening, a carry-iron and rockers rockable on said seats and carry-iron, said carry-iron being supported by said rockers and having a coupler-centering portion depending between the lower portions of said rockers.
3. In combination in a coupler-centering device, a striking plate, seats on opposite sides of a coupler opening therein, rockers bearing on said seats and a carry-iron suspended from upper portions of said rockers to depend therebetween, said carry-iron and rockers being adapted to have simultaneous displacement laterally of the coupler opening.
4. In combination in a centering device, a support having spaced rocker seats, upstanding rockers bearing on said seats and a carry-iron spanning the space between and articulated with the upper portions of said rockers and adapted to move to similarly incline said rockers either in one direction or the other and also to automatically center itself and said rockers.
5. In combination in a coupler-centering device, a striking plate having combined rocker seats and stops, upstanding rockers mounted therein and a carry-iron suspended from and between said rockers adapted to shift laterally with a coupler similarly inclining said rockers during such shifting, the stops co-acting with said rockers to cause the same and said carry-iron to be self-centering.
6. In combination in a coupler-centering device, a support having portions on opposite sides of an opening, upwardly projecting rockers internally mounted in said portions, a coupler-support entering said rockers adapted to be shifted to similarly incline said rockers, and means correlating said rockers and coupler-support to make the same self-centering.
7. In combination in a coupler-centering device, a striking plate, and a plurality of successively contacting coupler-supporting members some contacting with and being supported by said striking plate, there being a straight contact surface coöperating with an arcuate contact surface in each pair of contiguous portions of adjoining elements.
8. In combination in a coupler-centering device, an inverted U-shaped striking plate provided with U-shaped seats, upwardly projecting rockers mounted in said seats and a U-shaped carry-iron having substantially inverted U-shaped portions coöperatively engaging said rockers.
9. In combination in a coupler-centering

device, a striking casting having rocker seats on opposite sides of a coupler opening, reversible swaying rockers mounted in said seats, and a carry-iron borne by said rockers and adapted to be held at different altitudes by a reversal of the rockers.

10. In combination with a car end sill, of a striking plate secured to said car end and comprising spaced forward and rear walls, a carry-iron adapted to be inserted between said front and rear walls from beneath said striking plate, and rockable devices mounting said carry-iron to move laterally with a coupler and insertible into said striking plate to bear thereon at the rear of its front wall and above the bottom of the striking plate.

11. In combination with the end structure of an underframe, of a striking plate connected thereto and having front and rear walls internally shouldered to form spaced sets of seats, a double ended rocker between the seats of each set having trunnions bearing on the seats, a carry-iron connecting and mounted upon the upper portions of the rockers, said rockers being reversible to change the altitude of said carry-iron.

12. In combination in a coupler-centering device, a striking plate provided with spaced seats, a pair of reversible double ended rockers having trunnions rockable on said seats and a carry-iron mounted on the ends of the rockers that are uppermost, the opposite ends of said rockers and of said carry-iron being shaped to coöperate in preventing disconnection of said rockers and carry-iron.

13. In combination in a coupler-centering device, a pair of upwardly directed rockers, supporting seats on which they rock, and a carry-iron extending over and guidedly engaging the upper portions of said rockers, said carry-iron having depending hooks at its opposite ends adapted to engage said rockers, whereby said rockers and carry-iron may sway without disconnection from each other.

14. In combination in a coupler-centering device, a pair of upwardly directed rockers, supporting seats upon which they rock upturned at their ends to form stops, and a carry-iron engagingly extending over the upper end portions of said rockers and provided at its opposite end portions with stops, said rockers and carry-iron being adapted to sway and to be so restrained by said stops that they are self-centering by gravity.

In witness whereof I have hereunto set my hand in the presence of two witnesses.

JOHN M. ROHLFING.
